UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

PULLEY-BLOCK.

1,339,931.

Specification of Letters Patent. Patented May 11, 1920.

Application filed September 11, 1918. Serial No. 253,634.

To all whom it may concern:

Be it known that I, NILS D. LEVIN, a citizen of the United States, residing at Columbus, in the county of Franklin and State 5 of Ohio, have invented certain new and useful Improvements in Pulley-Blocks, of which the following is a specification, reference being had therein to the accompanying drawing.

10 The present invention relates to certain new and useful improvements in pulley blocks of the class adapted to be placed in operative relation with a rope midway of its length.

15 It is the especial object of this invention to provide a pulley block of the class described which may be securely attached to a machine frame or similar structure at points where it may be desirable to apply the draft 20 of a rope or similar flexible draft member, and which may be conveniently removed when such attachment becomes no longer desirable.

The devices by which I attain this object 25 are fully set forth in the following specification reference being had to the accompanying drawings of which—

Figure 1 is a plan view of the preferred embodiment of my invention in working 30 relation with the feed rope and frame of a mining machine, or similar device.

Fig. 2 is a view of the device illustrated in Fig. 1 with the frame part in position to permit engagement of the feed rope preparatory to attachment to the machine 35 frame.

Fig. 3 is a section along the line 3—3 of Fig. 1.

Fig. 4 is a fragmentary view of the frame 40 of a mining machine adapted to the attachment of my improved pulley block.

Figs. 5, 6 and 7 are diagrammatic figures illustrating the use of my invention.

Like numerals refer to similar parts in 45 the several figures.

In Figs. 5, 6 and 7 of the drawings I have, for the purpose of illustrating the application of my improved pulley block, diagrammatically illustrated a well known 50 mining and loading machine wherein the operative parts are mounted upon a sub base 1 adapted to rest upon and slide in any direction over the floor of the mine. This machine is provided with feeding 55 mechanism comprising a feed rope 2 which

is arranged to be connected to a suitably placed anchor jack 3 to move the machine bodily over the floor of the mine. Suitable guide sheaves 4 are permanently mounted upon the rear end of the sub base 1 and over 60 these the feed rope may be led from the tensioning device upon the mining machine to either side of the sub base. In Fig. 5 I have shown the arrangement of the feed rope 2 and anchor jack 3 to move the rear 65 end of the machine to the right. It is apparent that when the entire machine is to be moved laterally the strain of the feed rope must be applied at a point in the line between the anchor jack and the center of 70 gravity of the machine as illustrated in Fig. 6, and if the forward end of the machine is to be moved such strain must be applied near the forward end of the frame as shown in Fig. 7. If guide sheaves such as are 75 shown at 5 and 6 were permanently attached to the frame of the machine at all of the points at which it might be desirable to apply such strain, they would seriously interfere with the operation of the machine 80 near the side walls of the mine.

To avoid such interference I have provided my improved detachable pulley block comprising a sheave wheel 7 having its circumferential groove 8 adapted to engage 85 the feed rope 2 of such a mining machine or a similar draft member. The sheave wheel 7 is journaled upon a short shaft 9 mounted in apertures of two supporting brackets 10 and 11 which are held in working relation with said sheave wheel by the head 12 formed at one end of the shaft 9 and by a collar 13 secured at its other end by a suitable cotter pin 14. The brackets 10 and 11 are each independently rotatable 90 about the shaft 9 and each is provided with an inwardly extending flange 15 and 16 adapted to meet along the central longitudinal plane of the sheave wheel 7. The flanges 15 and 16 extend rearwardly from and at 100 right angles to the longitudinal central plane of the sheave wheel 7 and constitute a supporting foot having a flat surface 17 adapted to bear against the surface of the frame member 18 to which the pulley block is to 105 be attached. Formed at the forward end of the flanges 15 and 16 are companion lugs 19 the ends of which extend forwardly to form the hook 21 which together are adapted to extend through a suitable aperture 20 110

of the frame member 18 and to engage its inner surface to prevent movement of the pulley block away from said frame member. A cylindrical stud 22 formed of companion 5 semi cylindrical projections at the rear end of the flanges 15 and 16 is arranged to engage a second aperture 23 in the frame member 18 to prevent movement of the pulley block in any direction parallel to the surface 10 of said frame member. To apply my improved pulley block to a mining machine or similar structure the bracket 10 is first rotated relative to the bracket 11, as illustrated in Fig. 2, to permit placing the feed 15 rope 2 in the groove 8 of the sheave. The brackets 10 and 11 are then relatively rotated to bring their flanges 15 and 16 together and the stud 19 is inserted in the aperture 20 of the frame member 18. By a rear- 20 ward rocking movement of the brackets 10 and 11 upon the forward ends of the flanges 15 and 16 the hooks 21 may be brought into contact with the inner surface of the frame member 18, and the stud 22 inserted in the 25 aperture 23. Tension upon the feed rope 2 in the directions of the arrows in Fig. 1 tend to produce rotation of the parts about the hook 21 which holds the surface 17 in contact with the frame member 18. The 30 hooks 21 resist the outward strain of the feed rope 2 and the stud 22 resists its rearward strain thereby maintaining the desired relation of the sheave wheel 7 to the frame

of the machine. After the strain upon the rope 2 has been relieved the brackets 10 and 11 may be rocked forward to release the lugs 22 from the aperture 23 after which the hook 21 may be withdrawn from the aperture 20. While I have illustrated and described my invention with especial reference to its application to a mining machine I do not limit myself to such an application or the precise details of construction here shown as it is apparent that these devices may be subject to wide modification without 45 departure from the spirit of my invention.

What I claim is—

The herein described detachable pulley support formed in two similar halves, each half having a wide base plate formed with 50 a straight flat surface 17, adapted to bear against a base surface and having two hook halves 19, adapted, when registering, to form a single hook, and two pin halves 22, adapted to form a single pin to enter the base element, the pulley being mounted in the outer ends of said plates and held rigidly against displacement in any direction when the strain is on the cable.

In testimony whereof I affix my signature 60 in presence of two witnesses.

NILS D. LEVIN.
